UNITED STATES PATENT OFFICE.

CHARLES GILBERT AND W. G. HALLMAN, OF PHILADELPHIA, PENNSYLVANIA; SAID CHARLES GILBERT AND W. G. HALLMAN ASSIGNORS TO CHARLES GILBERT.

DESIGN FOR A STOVE.

Specification forming part of Design No. 342, dated January 1, 1851.

To all whom it may concern:

Be it known that we, CHARLES GILBERT and WITCHELL G. HALLMAN, of Philadelphia, in the county of Philadelphia and State of Pennsylvania, have invented or produced a new Design for a Parlor-Stove called "The Dolphin Radiator;" and we do hereby declare that the following is a full, clear, and exact description of the principle or character which distinguishes it from all other things before known, and of the usual manner of making, modifying, and using the same, reference being had to the accompanying drawings, of which—

Figure 1 is a view of one of the side flues in the shape of a dolphin; Fig. 2, a plan of the top plate; Fig. 3, a plan of the bottom plate; Fig. 4, an elevation of the front plate and doors; Fig. 5, an elevation of the side plate; Fig. 6, an elevation of the front base-plate with ash-pit door; and Fig. 7, an elevation of the side base-plate.

The drawings above enumerated show the detached pieces of a parlor-stove of a common form, but of a new and tasteful pattern. It consists of a base, Figs. 3, 6, and 7, ornamented with a foliated pattern with oval cen-

ters, the hearth-plate being surrounded with scroll-work, and having the words "Chas. Gilbert, No. 249 Nth. 2nd St., Phila., Dolphin Radiator, Patented 1850" in raised letters. Upon the base is erected the fire-box, Figs. 4 and 5, the front having two open-work doors and the sides being ornamented with a branching leaf and scroll pattern. Upon this rests the architrave, supported at the sides by four inverted dolphins, Fig. 1, and the whole is surmounted by the top plate, Fig. 2, which is raised in the center and ornamented with a leaf pattern radiating through apertures in a scroll. The border is an open-work scroll.

What we claim as our invention or production, and desire to secure by Letters Patent, is—

The ornamental design as above described, and represented in the accompanying drawings.

CHAS. GILBERT.
W. G. HALLMAN.
